US0D1087009S

(12) **United States Design Patent** (10) **Patent No.:** **US D1,087,009 S**
(45) **Date of Patent:** **** Aug. 5, 2025**

(54) **CHARGING STATION FOR MOBILE DEVICES**

(71) Applicant: **GN Audio A/S**, Ballerup (DK)

(72) Inventors: **Julie Tian**, Ballerup (DK); **Iain Scott Pottie**, Ballerup (DK); **Bill Zeng**, Ballerup (DK); **Alessia Zhang**, Ballerup (DK)

(73) Assignee: **GN AUDIO A/S**, Ballerup (DK)

(**) Term: **15 Years**

(21) Appl. No.: **29/879,781**

(22) Filed: **Jul. 12, 2023**

(30) **Foreign Application Priority Data**

Jan. 13, 2023 (WO) WIPO127476

(57) **CLAIM**

The ornamental design for a charging station for mobile devices, as shown and described.

DESCRIPTION

FIG. 1 is a Top, Front, Right Perspective view of a first embodiment of a charging station for mobile devices, showing our new design;

FIG. 2 is a Front view thereof;

FIG. 3 is a Rear view thereof;

FIG. 4 is a Left view thereof;

FIG. 5 is a Right view thereof;

FIG. 6 is a Top view thereof;

FIG. 7 is a Bottom view thereof;

FIG. 8 is a Top, Front, Right Perspective view of a second embodiment of the charging station for mobile devices;

FIG. 9 is a Front view thereof;

FIG. 10 is a Rear view thereof;

FIG. 11 is a Left view thereof;

FIG. 12 is a Right view thereof;

FIG. 13 is a Top view thereof; and,

FIG. 14 is a Bottom view thereof.

(Continued)

The features shown in broken lines depict portions of the charging station for mobile devices, that form no part of the claimed design.

1 Claim, 14 Drawing Sheets
